Des. 211,207
Patented May 28, 1968

211,207

NAILING MACHINE OR SIMILAR ARTICLE

Izaak Walton Bader, Brooklyn, N.Y., assignor to Swing-line Inc., Long Island City, N.Y., a corporation of New York

Filed June 29, 1967, Ser. No. 7,641

Term of patent 14 years

(Cl. D54—14)

FIG. 1 is an isometric perspective view of a nailing machine or similar article showing my new design.

FIG. 2 is a side elevational view thereof.

FIG. 3 is a front elevational view thereof.

FIG. 4 is a rear elevational view thereof.

FIG. 5 is a top plan view thereof.

FIG. 6 is a bottom plan view thereof.

The portions of the design not shown are similar to the portions shown.

The dominant features of my design reside in the portions shown in full lines.

I claim:

The ornamental design for a nailing machine or similar article, as shown and described.
